UNITED STATES PATENT OFFICE.

DANIEL GREEN, OF NEW YORK, N. Y.

SUITCASE-HANDLE.

1,156,993.

Specification of Letters Patent.

Patented Oct. 19, 1915.

Application filed January 16, 1915. Serial No. 2,606.

To all whom it may concern:

Be it known that I, DANIEL GREEN, a subject of the King of Hungary, and a resident of the city of New York, in the county 5 of Bronx and State of New York, have invented certain new and useful Improvements in Suitcase-Handles, of which the following is a specification.

The improvements in handles for suit-cases, forming the subject matter of the present invention, has for one of its objects the production of a simple and inexpensive substitute for a leather handle, usually applied on suit-cases of a more expensive character, which in appearance is very similar to a leather handle, but differs from the same by its durability, rigidity and convenience in being gripped by the hand, while, at the same time, it can be easily attached to a 20 suit-case of any convenient construction.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:—

Figure 1 is a vertical longitudinal cross section taken through a handle constructed in accordance with the present invention; Fig. 2 is a plan view thereof; Fig. 3 is a vertical cross section taken on line 3—3 of Fig. 1; Fig. 4 is a similar cross section on line 4—4 of the same figure; and Fig. 5 is a section taken through a modification of the invention.

In the drawings, the numeral 10 indicates a portion of a wall of a suit-case to which the handle is attached. The handle proper consists of a shell 11 of convenient cross section, having offset sides or shoulders 12, that extend substantially along the entire bail-shaped part of the handle. This shell may be made of sheet metal or similar material. 55 The shell is further provided with flat box-shaped end portions 13, which are angularly

disposed to the curved portion of the handle and of greater width than the shells forming the bail. These flat end portions are adapted to rest parallel to and upon the wall 10 of the suit-case. A second shell 14 of similar material, forming with the first shell a body of substantially oblong cross section is secured to the first shell by having its side portions 15 and 16 swaged upon the sides or shoulders 12 of the shell 11. The shell 14 terminates in end portions 17 and 18, forming with the side walls 19 and 20 of the end portions 13 of the shell 11 part of the box-like structures heretofore described. These flat ends are loosely held to the wall of the suit-case by means of loops 21 and 22, provided with lips 23 and 24, which are adapted to receive rivets 25 and 26 for securing the loops to the suit-case.

It will be noted that the shells form a practically integral rigid handle, which can be completed before the same is secured to the suit-case. It may be suitably painted to imitate the general appearance of the suit-case, or it may be provided with a leather cover, as customary in devices of this character. If desired the end portions of the handle may be directly secured to the walls of the suit-case by suitable fastening means, whereby the loops may be eliminated.

The modification shown in Fig. 5 of the drawings differs from the one above described in that along the shoulders 12 there are formed in the shell 11 grooves 27, in which the edges of the side portions 15 and 16 of the shell 14 are disposed.

What I claim is:—

1. A handle for bags or suit-cases comprising a rigid upper shell of bail-shape form provided with longitudinal shoulder portions of curved cross section, and a rigid lower shell having upwardly bent longitudinal edges overlapping and reinforcing the entire shoulder portions of said upper shell and forming with said upper shell a hollow body of substantially oval cross section.

2. A handle for bags or suit-cases comprising a rigid upper shell of bail-shape form provided with longitudinal shoulder portions of curved cross section, a rigid lower shell having upwardly bent longitudinal edges overlapping and reinforcing the entire shoulder portions of said upper shell and forming with said upper shell a hollow body of substantially oval cross section, box-shaped end portions on said up-

upper shell located in substantially one plane and being of greater width than said shell, and flat end portions on said lower shell entering the end portions of said upper shell.

3. A handle for suit-cases comprising a shell of bail-shape form provided with shoulders extending along the entire bail, a second shell adapted to engage the shoulders of said first shell and forming with the same a hollow body of substantially oval cross section, and box-shaped end portions on said body, angularly disposed to said bail and located in one plane, being of greater width than the shells forming the bail.

4. A handle for suit-cases comprising a

shell of bail-shape form provided with shoulders extending along the entire bail, a second shell adapted to engage the shoulders of said first shell and forming with the same a hollow body of substantially oval cross section, and box-shaped end portions on said body, angularly disposed to said bail and located in one plane, being of greater width than the shells forming the bail and integral with said first shell.

Signed at New York, in the county of New York, and State of New York, this 7th day of Jan., A. D. 1915.

DANIEL GREEN.
